UNITED STATES PATENT OFFICE

JOHN P. TEMPLEMAN, OF CHICAGO, ILLINOIS

SUPPORT FOR BRAKE-OPERATING MECHANISM

Application filed August 31, 1927. Serial No. 216,550.

This invention relates to railway brakes and more particularly to means for supporting the brake operating mechanism from the cars.

5 The principal object of the invention is the provision of a new and improved supporting means for the brake operating mechanism that is of universal application and that may be readily and easily assembled in position 10 on a railway car.

Another object of the invention is the provision of a new and improved brake operating unit that is adapted to be assembled as a 15 unitary structure and capable of use on any 15 and all types of cars without changes in the construction of the unit itself.

A further object of the invention is the provision of a new and improved support for 20 railway brake operating mechanism that is capable of universal use on cars and the like, that is cheap to manufacture and easily applied to the cars and that is not likely to become broken.

Other and further objects and advantages 25 of the invention will appear from the following description taken in connection with the accompanying drawings, in which—

Fig. 1 is a transverse vertical section of one 30 end portion of a railway car, showing the invention in position thereon, the same being taken on the line 1—1 of Fig. 2;

Fig. 2 is a view at right angles to that shown in Fig. 1, taken on the line 2—2 of Fig. 1;

Fig. 3 is a perspective view of the bottom 35 plate or member of the brake operating mechanism support; and

Fig. 4 is a perspective view of the bottom side of said plate.

There are many different types and forms 40 of street and railway cars and these different types often differ materially in their construction. In applying the brake operating mechanism to these different styles of cars, it is the common practice to provide a different and distinct form of brake operating mechanism supporting means for the different forms or types of cars. This is objectionable because it requires different moulds and tools for manufacturing the different types and also necessitates the repair 45 50

shops of the roads maintaining a sufficient supply of these different parts to meet all contingencies.

In order to avoid these objections the present invention seeks to standardize the brake 55 operating mechanism supporting plates or members. By means of applicant's construction the supporting members and brake operating mechanism may be assembled as a unitary device or structure, and by providing 60 means on this device for attaching supporting brackets of different lengths and forms, the device may be readily attached to any car by providing the proper shaped brackets or supports.

Referring now to the drawings in which similar reference characters are employed to designate the same parts throughout the description, the reference numeral 10 designates the end sill of a railway car and 11 a longitudinal sill thereof. Since the detailed construction of the car constitutes no part of the present invention it is not thought necessary to further illustrate or describe the same.

The brake operating mechanism 12 is supported from the sills 10 and 11 at the end of the car in a manner that will now be described.

The support 13 for this mechanism comprises a lower member 14 and an upper member 15 which are held in spaced relation by 65 any suitable means. As shown the lower member is provided with the flange 16 at each side thereof which is adapted to lap corresponding flanges 17 at each side of the upper member 13. The overlapping portions of the flanges 16 and 17 are provided with openings 70 for receiving the rivets 18 or the like. The upper member 13 is provided with an opening 19 for receiving the journal or hub 21 of the operating pinion 22. The lower end of the pinion 22 is provided with a journal 23 for engaging a corresponding opening or bearing 24 in the lower member 14.

The lower member 14 is provided with an offset portion 25 having a recess or opening 26 therein for receiving the lower end of a hub or journal for the brake drum 27. The upper member is provided with a corresponding recess or opening 28 for receiving the upper end of the drum journal. A rivet 100

or bolt 29 extends through the axis of the drum and the upper and lower supporting members 13 and 14, for holding the parts in assembled relation. The drum is provided with a gear 31 which is adapted to mesh with the pinion 22, as is usual in such constructions. The pinion 22 is adapted to be rotated by the brake staff 32, in a manner well known in the art. Since the details of the 10 brake operating mechanism or gears constitute no part of the present invention, it is not thought necessary to further illustrate or describe the same.

The upper and lower supporting members 15 13 and 14, with the gearing secured therein, constitute what, for convenience, will be termed a brake operating unit.

The brake operating unit comprising the upper and lower supporting members 13 and 20 14 and the operating mechanism carried thereby may be employed on any type of car, it only being necessary to provide suitable brackets or supporting arms for securing the same to the particular car. It has been the 25 common practice to supply each different type of car with a different brake operating mechanism support, but with the present invention it is only necessary to provide different bracket supporting arms. The unit may be supplied without these brackets, which may be readily attached at the time the unit is installed.

Any suitable means may be provided for supporting the brake operating unit. The 35 form of construction shown is by way of example only, since these supporting brackets or arms will differ widely depending on the type of car on which they are employed.

As shown, a plurality of arms 20, 30 and 40, are employed for this purpose. These arms are bent or forged to the required shape and are rigidly secured to the brake operating unit. Any suitable number of arms or brackets may be employed. They are rigidly secured at their inner ends to the unit and at their outer ends to the adjacent end and center sills, or to any other convenient portion of the car, as necessary or desirable. The inner ends of the supporting brackets are secured to the unit in any suitable manner. As shown, the bottom portion of the lower supporting member 14 is provided with a pair of recesses 33 and 33^a at each side thereof. These recesses are provided with openings 34 and 35 in their bottom walls (see Fig. 4) for the reception of fastening bolts or rivets 36 (see Fig. 1), for holding the ends of the supporting arms in position in said recesses. The bottom wall of the recesses may be, and 60 preferably are, provided with integral studs 39 which may be headed over for holding the attaching brackets in position. These studs may be replaced by bolts or rivets, if desired.

In the form of the device shown in Fig. 1, 65 only three supporting arms 20, 30 and 40 are

shown. These arms are bent, forged, or cast, to the proper form and the arms or supporting brackets 30 and 40 are rigidly attached at their outer ends to the lower flanges of the longitudinally extending beams or center sills 70 11, as at 42, and the supporting arm 20 is attached to the end sill 10. In the form shown, these supporting arms are sufficient, although a recess is provided for receiving a fourth if it is found to be desirable. 75

It will thus be seen that the brake operating unit comprising the upper and lower supporting members and the operating mechanism may be assembled as a unitary structure and is then adapted for universal application. To attach the unit to any car it is only necessary to supply brackets or supporting arms of the necessary length and shape. When attached the brake staff is slid into position and the device is completely installed 80 and ready for use. While I have disclosed the operating mechanism as comprising reduction gearing, it is understood that any type of operating mechanism may be employed as the particular type of mechanism is 85 immaterial so far as the present invention is concerned.

It is thought from the foregoing taken in connection with the accompanying drawings that the construction and operation of my device will be apparent to those skilled in the art, and that various changes in size, shape, proportion and details of construction may be made without departing from the spirit and scope of the appended claims. 95

I claim as my invention:

1. A supporting casting for a railway brake operating mechanism adapted for universal application, comprising a plate having a staff opening therethrough, said plate being provided with an offset portion having a bearing for said mechanism, and provided with recesses on the under face thereof for receiving the inner ends of supporting members. 105

2. As an article of manufacture, a casting comprising a plate having a brake staff bearing therein and upwardly extending apertured projections at each side thereof, a gear supporting plate, offset from said first named plate and provided with an opening for receiving a gear journal, and a slotted connecting member between said plates, said plates being provided on their under sides with recesses for receiving the ends of supporting members. 110

3. As an article of manufacture, a casting comprising a plate member having an offset, said plate having upstanding flanges thereon and provided with an opening for receiving the brake staff, said offset portion being provided with an opening for receiving a gear journal and said casting being provided with means on both the plate member and offset portion for attaching supporting brackets rigidly thereto. 125

4. A supporting member for a railway brake operating mechanism comprising a plate member having an opening at one end for receiving a brake staff journal and an opening at its other end for receiving a journal of said mechanism, said plate member having recesses on its under side for receiving the inner ends of supporting elements, the bottom walls of said recesses being provided with openings for the reception of means for securing said supporting elements to said supporting member, and apertured flanges extending upwardly from each side of said member.
5. A supporting casting for a railway brake operating mechanism comprising a supporting member having an opening for receiving a brake staff journal and having an opening in its opposite end for receiving a gearing journal, upwardly extending apertured flanges at each side of said member and means for attaching supporting elements to said member.
6. A brake operating mechanism supporting device of universal application comprising a lower member, an upper member, means for connecting said members together and holding them in spaced relation for receiving a brake drum, said members having aligned bearings for the brake operating mechanism, said lower member being provided with means on the bottom thereof for attaching supporting bars thereto.
7. A brake operating mechanism supporting device as a unitary structure adapted for universal application to railway cars, comprising a lower member, an upper member, and brake operating mechanism between said members, said device being free from supports but being provided with recesses on the bottom thereof adapted to have supporting brackets rigidly attached thereto.
8. A casting for supporting device for railway brake operating mechanism comprising, a plate member having a downwardly offset portion, said plate member being provided with an upwardly extending apertured flange member at each side thereof and having an opening for receiving the brake staff, said offset portion being provided with an opening having a counterbore, said plate and offset portion being provided with recesses, each having an opening in its bottom wall, and a stud projecting outwardly therefrom for attaching brake hanger members thereto.

In testimony whereof I affix my signature.
JOHN P. TEMPLEMAN.
